HIS ATTY.

UNITED STATES PATENT OFFICE.

ORANGE O. OZIAS, OF DAYTON, OHIO.

DESIGN FOR A SCALE BASE MEMBER.

SPECIFICATION forming part of Design No. 33,828, dated January 1, 1901.

Application filed July 6, 1900. Serial No. 22,768. Term of patent 7 years.

To all whom it may concern:

Be it known that I, ORANGE O. OZIAS, a citizen of the United States of America, residing and having my post-office address in Dayton, 5 in the county of Montgomery and State of Ohio, have invented and produced a certain new and original Design for a Scale Base Member; and I hereby declare that the following is a clear, full, and exact description thereof, 10 reference being had to the accompanying drawings, in which like numerals refer to like parts.

Figure 1 in the drawings illustrates a top plan view of a design for a scale-base member formed in accordance with my invention and design, and Fig. 2 is a front elevation view thereof.

The leading or material feature of this design consists of a rectangular member hav-

ing projections from one side and a curved 20 member upon one end thereof extending at an angle to said rectangular member.

In said drawings, 10 represents the rectangular member, 11 represents the projections from one side thereof, and 12 represents the 25 curved member upon one end thereof and extending at an angle to said rectangular member.

What I claim is—

The design for a scale base member, substantially as shown and described.

In witness whereof I have hereunto set my hand this 28th day of May, 1900.

ORANGE O. OZIAS.

Witnesses:

L. D. HELLER,
IRA C. KOEHNE.
